UNITED STATES PATENT OFFICE.

ALEXANDER S. SPEER, OF BUFFALO, NEW YORK, ASSIGNOR, BY MESNE ASSIGNMENTS, TO THE BEAVER PRODUCTS COMPANY, INC., A CORPORATION OF NEW YORK.

COMPOSITION ROOFING.

Original application filed December 28, 1920, Serial No. 433,623. Divided and this application filed May 19, 1921. Serial No. 470,914. Renewed October 25, 1923.

To all whom it may concern:

Be it known that I, ALEXANDER S. SPEER, a citizen of the United States, residing at Buffalo, in the county of Erie, State of New York, have invented certain new and useful Improvements in Composition Roofing; and I do hereby declare the following to be a full, clear, and exact description of the invention, such as will enable others skilled in the art to which it appertains to make and use the same.

This invention relates to improvements in composition roofing and analogous building material or the like and particularly to such material having identifying data thereon such as trademarks or the like.

Among other objects the invention is intended to provide composition roofing or the like, such as asphalt roofing having designs or marks on one side thereof which do not result in any marring of the face side of the material but which, nevertheless, are clear and distinct and cannot be readily obliterated.

In the drawings,

Figure 1 is a perspective view of the printing and platen rolls,

Figure 2 is an enlarged transverse section of a part of the printing roll.

In the manufacture of composition roofing, it is desirable to impress data, as for instance a trademark, upon the under face, that is that face of the web or sheet which will not be exposed to the weather. It is also desirable to make the impressions while the roofing is in course of manufacture, that is before it passes from the machine on which it is made. At this time the web or sheet is in a warm and plastic condition, and relatively soft, so that it is difficult to impress a mark of sufficient depth to prevent obliteration in handling, without marring the opposite face of the web. If considerable pressure is used, that portion of the web containing the impression will be offset, presenting an embossed surface on the opposite face.

In order to obtain a clear-cut impression, without any offsetting of that portion of the web containing the impression, I use a die having raised printing characters of greater height than the depth of the impression desired, and I so limit the move-

ment of this die toward the web during printing or impressing, that only a portion of the depth of the printing characters will enter the material of the web and the blank surface of the die will not contact with the web. Thus the impression is cut in the web. In order to prevent sticking of the material to the die, I keep the surface of the die and of the roll upon which it is mounted lubricated by any suitable material, as for instance soap water, or kerosene.

In the manufacture of the composition roofing, a body of felted material is provided, as for instance of shredded rags and the like, and this body is immersed in asphaltum of a suitable consistency and saturated therewith. One face is then faced with pitch, and upon the pitch a mineral in a crushed state is placed, and in laying the roofing, it is this face having the crushed mineral which is to the weather. The impressions or designs are on the reverse face, and the said designs or impressions are made while the finished web is warm and plastic.

In the mechanism shown, the web 1 as it passes from the machine on which it is formed, is passed between a pair of rolls 2 and 3, the former being a printing roll, while the latter is a platen roll, and one of the rolls is mounted to yield away from the other, to compensate for various thicknesses of the web, and to prevent injury from lumps of asphalt and the like which may be upon the web.

The printing roll has upon the peripheral surface thereof a series of depressions 4, the depressions corresponding in spacing and arrangement to the spacing and arrangement of the impressions desired upon the web. Within each of these depressions there is arranged a die 5, the said dies having printing characters 6 which extend above the surface of the die in the usual manner, and these characters have sharp edges in order that they will cut the web. The characters are of greater height than the depth of the impression desired, and the blank surface of the die is spaced within the peripheral surface of the roll, so that that portion of the web which receives the impressions is engaged only by the printing characters, and not by the blank surface of

the die. Thus there is no pressure on the web at this point other than the pressure of the printing characters themselves. The printing roll may be arranged above or below the web, depending upon the character of the material being manufactured. For instance, roll roofing is cut with the weather or top side down, and in operating upon this material, the printing roll should be 5 above. In cutting shingles from the web however, the weather side is up and the printing roll should be below the web in order to impress the designs on the bottom of the web. In either case the printing roll 10 is lubricated, with any suitable lubricant, as for instance soap water or kerosene, and in the arrangement shown the printing roll 2 runs in contact with a roll 7 having a facing 8 of felt or like absorbent material. This 15 facing is soaked with the lubricant, in any suitable manner.

In making the impressions, it is essential 20 that they be alike, regardless of the thickness of the web and of its consistency. If 25 the impression or design is cut too deeply, the web will tear, and if it is too shallow, it will be obliterated in handling. The arrangement of the die as above described, with only those portions of the characters 30 extending beyond the peripheral surface of the roll which actually penetrate the web insures that the impressions will be cut to the same depth regardless of the thickness of the web and of its consistency.

35 This application is a division of my application Serial No. 433,623, filed December 28, 1920.

I claim:—

40 1. As an article of manufacture, a composition sheet or web having its under face provided at regular intervals with impressions or designs cut in said face.

45 2. As an article of manufacture, a composition sheet or web having its under face provided at regular intervals with impressions or designs cut in said face, the im-

pressions being similarly arranged and in a definite pattern.

3. As an article of manufacture, a composition roofing shingle comprising felt saturated with asphaltum and having its top 50 faced with pitch and a crushed mineral, the lower face of said shingle being provided with a design cut therein, substantially as described.

4. As an article of manufacture, composition roofing comprising felt saturated with asphaltum and having on its top a layer of pitch, the under surface of said felt bearing 55 a design cut therein while said asphaltum was warm and plastic, substantially as described.

5. As an article of manufacture, composition roofing comprising felt saturated with asphaltum and surfaced as usual with 60 crushed mineral, the under surface of said roofing bearing a trade mark cut into the felt, substantially as described.

6. As an article of manufacture, a sheet 65 of relatively soft building material provided on its under side with a design or trademark formed by relatively thin lines cut into the material.

7. As an article of manufacture, trademarked building material, such as asphalt 70 roofing or the like, having on its under side at intervals a trademark or other identifying data, the outlines of which are formed by relatively narrow cuts into the under side of the material which do not displace or 75 mar the outer face of the material.

8. As an article of manufacture, asphalt roofing having an outer or wearing surface and provided on its under face at regular 80 intervals with designs or identifying data formed by lines consisting of knife-like cuts into the under face of the material which do not disturb or mar the wearing face of the material.

In testimony whereof I affix my signature.

ALEXANDER S. SPEER.
